UNITED STATES PATENT OFFICE.

THEODORE DOUGLAS, OF SCARBORO, NEW YORK, ASSIGNOR TO DUPLEX ENGINE GOVERNOR COMPANY, INC., OF BROOKLYN, NEW YORK, A CORPORATION OF NEW YORK.

SAFETY ATTACHMENT FOR AIRCRAFT.

Application filed January 24, 1919. Serial No. 272,958.

The invention herein set forth relates to an attachment for aircraft; and aims to provide an instrument which can be combined with the power system embracing the 5 engine of the airship in such a way that, whenever a shock involving the engine occurs, the operation of the latter is interrupted at once by the automatic suspending of the operation of the ignition system supplying electrical current to the cylinders of the engine to produce combustion of the fuel therein.

My invention is designed for airships with one or more engines, and is capable of acting 15 in case of emergency, to affect and control the ignition system by either open-circuiting or short-circuiting the same, thereby affording the attainment of the desired end.

An object of my invention is to provide 20 an attachment which will be simple in construction and capable of being easily applied and connected in operative relation so that it will instantly and infallibly take effect under predetermined conditions to 25 avert serious consequences before the aviator can take measures by hand to insure his own safety and the safety of his machine.

It very often happens when an aviator is making a flight that a propeller blade 30 breaks or something else happens; making the engine immediately become unbalanced and wrench itself loose from its anchorage. Frequently in such cases the gasoline line is broken, and fire has been known to start 35 as a consequence of the continued sparking in the engine cylinders and the flaming exhaust into the atmosphere before the aviator has time to manipulate the main switch of the ignition circuit; even when such switch 40 is easily within his reach. Under such circumstances the engine may not only tear itself from its fastenings, but even go overboard before the aviator can fully realize what has come to pass; and when fire due 45 to the escape of gasoline commences, the end of both flier and flying machine may follow.

Such breakages are infrequent under ordinary conditions, but likely to happen, from 50 gunfire and accidentally, in war. In an aerial engagement, the objective is to put either the hostile flier or his machine out of commission; therefore the pilot and the machine carrying him are the important targets. Now, when an aviator is in action he

needs his hands for his weapons and his feet 55 and knees for his controls. Should a blade break or be shot off at a critical moment he has small chance of saving himself; for even if he recovers the management of his machine, he necessarily sacrifices altitude; which is priceless and generally determines whether he can get back over the enemy's barrage into his own territory.

My invention eliminates the danger from accidents such as I have just outlined by mechanism which is quite simple, involving relatively few parts and comprising no construction which is bulky, complicated or expensive; and which can be mounted upon an airship so that it will instantly respond 70 to an abnormal vibration or other bodily movement of the engine driving the same, in order to cut off the flow of ignition current to the spark plugs and cause the engine to stop developing power. In this way, in case 75 a propeller blade should break, or something else should happen to unbalance the engine, the danger of the latter tearing itself loose and causing a destructive fire is fully obviated. Hence the instrument does not in 80 any way interfere with the airship but on the contrary is of great utility; making the pilot free for his fight with the enemy and enabling him to sail about and maneuver aloft in complete confidence.

Other objects and advantages of my invention will more clearly appear from the following description, taken in connection with the accompanying drawings forming a 85 part of the same; and the characteristics of my invention will be precisely defined in the appended claims. This disclosure, however, is explanatory only, and I reserve the right to adopt embodiments of my invention other than what is actually shown herein to the full extent indicated by the general meanings of the terms in which the claims are expressed.

On the drawings:—

Figures 1 and 2 are top and bottom views 100 of the casing of an instrument according to my invention;

Figure 3 is a view of said casing and contents, without the cover;

Figure 4 is a section on line 4—4, Figure 105 3;

Figure 5 is a bottom plan of the cover of this instrument;

Figure 6 shows diagrammatically circuit connections therefor; illustrating the manner in which the invention is combined with the ignition system;

5 Figures 7, 8 and 9 are top, bottom and end views of a switch for the instrument;

Figures 10 and 11 show top and bottom views of the casing of a modified form of instrument;

10 Figure 12 is a view thereof, similar to Figure 3;

Figure 13 is a section through Figure 12 similar to Figure 4;

15 Figure 14 is a bottom plan of the cover of this modification; and

Figure 15 shows a diagram of the circuits for same.

The invention described hereinafter is an improvement upon a similar invention set forth in my copending application, Serial Number 209,130, filed December 27, 1917.

The same numerals identify the same parts throughout.

20 Referring to the first two figures on the drawings, I show one form of my safety attachment for the power system of an airship as a whole at 8. The arrangement of the parts of this attachment is such that, as I shall set forth fully hereinafter, the attachment will automatically cut off the ignition current by open-circuiting the ignition system and it is adapted to be operated by any abnormal bodily movement of the engine, as when there is an unbalanced condition resulting from a broken propeller blade.

25 In that event the torque of the engine, which would be normally divided by the blades and thus produce a balanced load, is then no longer properly divided; pro-

30 ducing a badly unbalanced load, and jerking or pushing the engine from side to side as the propeller revolves. Under such circumstances a tractor plane is liable to go into a dive; a pusher plane into a tail stall; and either is apt to pass next into a tail-spin, and the engine may or may not go overboard entirely. If this side pressure does become so great that the engine is broken from its

35 foundation and thrown out of the airship, the center of gravity of the machine is upset, completely destroying its equilibrium, and effecting other and more serious damage.

40 The attachment 8 produces a suspension of the operation of the ignition system to stop the engine chiefly through the instrumentality of an element such as a pivotally mounted bar 11, comprised in the attachment 8, and housed in a casing 12. See Figure 3. This bar has sufficient mass, and

45 it is supported upon its pivot 13 in the casing 12, so that it can move or swing or oscillate, like a pendulum, in a direction that extends across or transversely of the longitudinal axis of the engine; that is the bar should preferably swing parallel to the

50 plane of the propeller. I may secure the attachment 8 to any part of the aeroplane so related to the engine that any transverse jar will instantly be transmitted to the bar 11; hence I can mount the attachment either upon some part of the engine framework directly, or upon a part of the aeroplane or other airship rigid with it, such as the instrument board in the pit of the fuselage; or near enough to it to be subject to its vibration, such as one of the engine bearers when in the wings. Preferably the casing 12 and bar 11 are both in vertical position, and the bar, to stop the engine, swings in a direction transverse to the crankshaft 55 thereof. I may also mount the casing 12 so that it will be horizontal and the bar 11 will normally lie parallel to the crankshaft. However, the car 11 will still be in position to swing in a direction transverse to the crankshaft, and the attachment can therefore perform its function when needed quite as easily as in the first instance, to respond to a transverse shock from the engine 60 as a result of its unbalanced torque reaction.

65 The casing 12 and parts borne thereby are illustrated, particularly in Figures 3 and 4. It comprises sides and ends; to which is secured a bottom 20; and a removable cover 21. The sides, ends, bottom and cover of the casing are preferably of some insulating substance, such as fibre or rubber. To the bottom 20, near the upper end of the casing is fixed an inverted metal yoke 22 in which is carried the pivot pin 13 whereon the bar 11 is hung. As will appear presently, whenever the bar or element 11 is constrained to swing sidewise, it acts very promptly in the required manner.

70 On the outside of bottom 20 of the casing 12 are located four electrical terminals or binding posts 25; extending into the casing and each joined to a conductor 73. These binding posts enable the instrument to be connected into the ignition system and the 75 conductors lead to the parts in the casing that are embraced in the circuit or circuits of same.

75 At a distance from the pivot 13 to one side of the bar 11 is a compression spring 42^a. The free end of the bar 11 carries a pin or handle 45 which projects through a slot in the adjacent end of the casing; and to this pin are secured two other springs 46, one at each side. The spring 42^a and the springs 80 85 90 95 100 105 110 115 120 125 130 135 140 145 150 155 160 165 170 175 180 185 190 195 200 205 210 215 220 225 230 235 240 245 250 255 260 265 270 275 280 285 290 lating the nuts 50^a the bar 11 can be moved to exact central position; and it will so remain until occasion requires it to swing away from central position. The springs 5 46, with the nuts 50^a thus serve also as means for adjusting the bar 11 in addition to damping it, and by means of the nuts 50^a, the tension of the springs 46 can be changed as desired.

10 The spring 42^a is carried at one side of the casing near the springs 46, upon a screw 67 in a threaded bearing 68, in the side wall of the casing. This bearing is situated in a threaded boss 69, closed by a nut 70, in the 15 bore 71 of this boss. A kerf in the screw 67 permits turning the screw from the outside of the casing by a tool when the nut 70 is removed.

Each spring 46 is attached to a plug 72 20 projecting through the adjacent nut 50^a, which engages threads inside the boss 49. These nuts receive heads on the plugs 72 and the nuts can be shaped in any suitable way to be turned by a tool or other device, from 25 without the casing and regulate the springs 46. Closures for the outer ends of the bosses 49 may be provided.

At the right, inside the casing, are two 30 conductors 73, each leading to an element 23 on the bottom 20, mounting a pivoted element 74, extending over bar 11 and carrying a shoulder 36 to engage a dog 75 on a rotatable spindle 76 at the left. Each spindle 76 has an arm 77, secured to a tension-spring 35 78 anchored in a recess in the bottom of casing 12. These springs force the dogs 75 against the shoulders 36^a. Other elements 23 on the bottom 20 mount the spindle 76 and are connected to similar conductors 73 40 in the casing 12. All conductors 73 are joined to binding posts 25 on the back of the casing. Each element 74 has a cam face 79 and the bar 11 carries round-ended steel screws 80 to engage the cam faces 79.

45 A transverse shock causes the bar 11 to move the elements 74 upward, releasing the dogs 75. To free these dogs 75 simultaneously I place the screw 80 which is nearer to the pivot 13, so as to be adjacent the left 50 side of the bar, and the other screw 80 at the right side. The bar is recessed at 81 adjacent the latter screw to give the adjacent cam face 79 sufficient clearance till this other screw strikes it.

55 This instrument is for engines having two distributors and is connected so that each element 74 is joined in series with the main circuits of the ignition system. See Figure 6. In this view two electrical generators, such as batteries or magnetos are shown at 82. Each is in series through suitable conductors with one of the elements or triggers 74; and from the attachment 8 the current from those generators passes to suit-

able translating devices 83, which may represent distributors. These distributors supply high tension current to the spark plugs of the engine by turns, the current from each generator being stepped up before it passes through the distributor by suitable means, such as a transformer, or induction coil. The engine will have two sets of igniters, one set supplied from one generator and distributor and the other set by the remaining distributor and generator. Hence each 75 cylinder of the engine will have two spark plugs and both sets of igniters may be used together, or only one at a time, with one of the generators and distributors, may be in service; the other set, with the remaining 80 generator and distributor, being kept in reserve, as an auxiliary or relay, to be thrown in if the first set fails or ceases to work properly. A shock will open the circuits of both generators and distributors at once. The bar 11 is insulated, and elements 23 and 74, the dogs 75 and the spindles 76 conductive.

My invention is of course useful on pusher planes as well as tractor planes; and on 90 dirigible balloons; because when a propeller on a balloon breaks, fragments may puncture the gas bag and liberate the inflammable contents.

When an accident happens the flier hardly ever has time to do anything to save himself, even if he remains calm and uninjured. With the attachment 8, ignition is automatically terminated within a fraction of a revolution of a high-powered engine; and if gasoline is spilled, fire does not ensue.

Casing 12 may also be placed parallel to the wings if the bar 11 is arranged to swing transversely of the engine.

The force of the springs on each side of the bar 11 is of course adjusted to make the attachment 8 inoperative within the limits of the safe operation of the engine; causing 100 the pendulum bar to remain neutral until that limit is exceeded.

It sometimes happens too that when an aviator is making a flight an accident may happen in some other manner than by the breaking of a propeller blade, and may cause a shock to the engine that is more or less parallel to the axis of the crankshaft instead of transverse to the same. Such a situation may result from a collision. If it is desired to guard against such a thing, the attachment 8 can be mounted so that the casing 12 will have its top 21 and bottom 20 parallel with the crankshaft of the engine, and with the bar in vertical or horizontal position, but transverse to the crankshaft of the same. With this arrangement a collision 115 producing a substantially longitudinal shock will cause the bar to swing in a plane that is more or less parallel with the engine 120 125

crankshaft, and suspend the operation of the ignition circuit with the same result as in the first instance.

Furthermore, in order to guard against a mishap of both kinds; that is, anything that might produce a transverse shock to the engine or a longitudinal shock also; I may use two of my attachments 8 with the same engine, by mounting one so that the bar will

- 10 be able to swing in a direction transverse to the crankshaft and the other so that the bar can swing in a direction that is more or less parallel with the crankshaft. The two instruments may both be arranged, for example, so as to suspend the ignition, whichever one takes effect, by connecting the two instruments in series with each other; that is to say, simply by adding another instrument to the one shown in Figure 6, and connecting it in circuit with the generators, etc., in the same way. Then in case of a collision, whichever of the two instruments allows its pendulum bar to swing in a direction parallel to the crankshaft will cause the opening 25 circuiting of the ignition system; and in case a shock occurs transversely of the engine, the other one will produce the required effect. With two attachments on an aeroplane, the ignition can be interrupted in 30 case of an accident that is caused by practically any shock to the aeroplane substantially parallel to the plane of the wings, whether longitudinal or transverse, or even in a diagonal direction; although the mode 35 of operation will be best and surest of course when the shock is either directly transverse or directly along the length of the engine.

The spindles 76 also each have an arm 84, beneath a projection 85 on a plunger 38 in 40 the cover 21. After the dogs 75 are released, the pressing of this plunger, through the arms 84, turns the spindles 76 to reengage the dogs with the shoulders 36^a. A spring 45 engages the head of the plunger and the cover to force the plunger normally outward with respect to the casing.

The spindles 76 also have arms 86, one on each spindle, which press against slide members 87; said members being in grooves, not 50 shown, on the inner face of the cover 21, beneath openings 88 therein; and engaged by springs 89 upon projections carried by strips 90. See Figures 4 and 5. When the elements 74 hold the dogs 75, the arms 86 force 55 the members 87 to keep cross-marks thereon out of registry with openings 88. These marks come into registry with the openings 88, when the elements 74 release the dogs. By luminous paint these marks may be made 60 visible at night and they tell whether or not the instrument is ready. The strips 90 retain the members 87 in place on the inner face of the cover and have slots to receive downturned ends of the members 87 abutting 65 the springs 89. (Figure 5.) The pro-

jections on these strips engaging the springs 89 are at the opposite ends of the slots, and the downturned ends of the members 87 can move freely in these slots, as will be understood.

In Figure 1, the cross marks appear. But with the elements 74 and dogs 75 as in Figure 4, the marks will not be visible.

Figures 7, 8 and 9 show a switch comprising insulation 91 carrying two conductive members 92, between which are two pairs of spring contacts 93, one pair at each side. The contacts at the left are joined to binding posts 25 at the left, by strips and screws passing through the insulation 91. (Figure 80 8.) The contacts at the right are disconnected. Bearing members 92 are joined by screws and strips on the bottom of the insulation 91 to the binding posts 25 at the right; and support a handle 94 of insulation, 85 carrying separated metallic strips 95 having trunnions 96, to pivot it. This switch is to be in multiple with the instrument 8 (Figure 90 6), the two upper posts being connected in the line of one generator 82, and the remaining posts in the line of the other. With handle 94 to the right (Figure 7) the two upper posts are bridged, likewise the two lower posts, and the instrument is shunted out. When thrown to the left the switch 95 moves the metallic strips 95 upon the contact springs 93, at the right, and the binding posts will be disconnected, throwing the instrument in. Stops 97 on the members 92, 100 limit the throw of the switch. This switch in some cases can be mounted directly on the cover 21.

Figures 10 to 15 inclusive illustrate a modification having a single catch 34^a over the bar 11, engaging a single dog 75 on a single spindle 76 in the casing 12. On the back of the casing are right and left binding posts 25, connected to conductors 73 on the inside of the casing. One of these conductors extends to and is electrically connected with a contact element 98, secured to the bottom of the casing 12, and having a projection 99, bearing against the spindle 76. The other conductor 73 leads to a contact element 100, fast under the element 23 115 which supports the spindle 76. This element has a projection 101 bent towards the dog 75. Below this projection is another contact element 102 to be grounded through a third conductor 73. Whenever the dog 75 120 is liberated it presses the projection 101 upon the terminal 102, grounding both conductors 73, connected to the right and left posts 25.

The terminal 102 is joined to an element 125 103 on the bottom of the casing in circuit with the element 104 carried by the cover 21. A switch on the outer face of the cover 21 comprises springs 93, the left spring being connected to the element 104 and the

other spring at the right being dead. See Figures 10 and 13. The handle 94, of insulation, has a metal inset 95^a to engage the springs 93. A pivot or trunnion on the handle engages the member 92 and connects electrically with the metal inset 95^a. One member 92 is insulated; the other is in circuit through a metal strip 105 on the cover 21 with the third conductor 73, and third 10 binding post 25^e on the back of the bottom of the casing. When the switch is thrown to the right, the elements 104 and 105 will be connected, and disconnected when the switch is thrown to the left. Figure 15 shows the diagram of circuits. This instrument is for engines with two ignition circuits, supplied with ignition current from two magnetos 3; and grounds both magnetos through the post 25^e. One magneto serves 20 for one circuit and the other for the remaining circuit and as many spark plugs will be connected to each magneto as there are cylinders to the engine associated therewith. The spark plugs may be utilized as before 25 with both magnetos, both circuit and all the plugs in service at once; or only one ignition circuit with one magneto and one set of plugs may be active, the other circuit with its plugs and magneto being in reserve. 30 These spark plugs are indicated diagrammatically at 2. This instrument too may be made up with the switch separate.

Both the above-described instruments have springs 41 engaging parts 74 and 34^a, and 35 surrounding stems passing through holes in these parts and receiving the adjusting nuts 107 to regulate the springs.

Both instruments can be employed on not only airships having one engine with two 40 ignition circuits, but also twin-engined machines; with two propellers; as an accident to one engine would cause the other to swing the plane around into a dive and perhaps into a tail spin. This usefulness for twin-engined machines is especially the case with 45 the instrument shown in Figures 1 to 5 inclusive. On a twin-engined machine there will be two such instruments, one associated with each engine; and the wiring must be such that each instrument must be included 50 in the ignition circuit or circuits of both engines. Then the breaking of a propeller driven by either engine will result in actuating the bar 11 of the instrument associated 55 therewith; and the ignition circuits of both that engine and its mate will be affected instantly. Hence both engines will be immediately made to cease developing power simultaneously. A switch like that shown in 60 Figures 7, 8 and 9 will be arranged to shunt out both instruments when desired. After a mishap, the pilot can cut out the two instruments and land with dead engines, or switch on his undamaged engine and continue with it at reduced speed.

When the cover in Figure 14 is applied, the element 103 may be connected to element 104 and the element 105 to the third conductor 73 by metal screws passing through metallic bosses in the cover into metallic 70 sockets in the bottom casing. Additional screws, bosses and sockets may be employed to hold the cover on the casing, both in this modification and the preceding. (Figure 1 above openings 88 and Figure 14 at the ends 75 of the switch.)

The casing for both instruments is shown of insulation, but may be of metal with an insulating cover, and a bottom insulated from the sides. The instrument last shown 80 in Figures 10 to 14 inclusive may also be used to guard against transverse shock or collision, or both. In view of a propeller blade breaking, the bar 11 will be arranged as before to swing transversely of the airship; and longitudinally in case of a collision. To guard against both kinds of accident two instruments shown in Figures 10 to 14 inclusive are put in parallel with each other and with the ignition circuit, one being 85 mounted to let the bar swing transversely and the other longitudinally of the engine, as set forth above.

Springs 46 and 42^a prevent operation of the bar 11 to suspend ignition, from misfiring or shocks in landing. The instrument does not interfere with the ignition.

When there is one engine and the engine and propeller are on the fuselage, the instrument is placed in the pit or on the instrument board; with the switch directly on the casing 12. When there are two engines and each engine is mounted in the wings of an aeroplane, the instrument is placed preferably on one of the engine bearers, in a weather proof covering. The switch is then mounted in the pit.

The outer end of the plunger 36 and switch handle may also be touched with luminescent paint.

To test these instruments before flying, one starts the engine and moves the bar 11 by the handle 45 to the left till the cross marks appear at the opening or openings 88. Before the engine stops the instrument is 115 reset by pressure on the plunger 38, till the marks disappear again. Either of these two instruments can be used also on an engine having a single ignition circuit and one set of spark plugs.

My invention may be used on prime movers other than gas engines, if provided with electric circuits essential to regular operation.

The types of instruments shown in Figures 1 to 5 inclusive, and Figures 10 to 14 inclusive are alike in their main characteristics. Each comprises a bar or element 11 for affecting an electric ignition circuit, either by breaking it or grounding same;

- and in each there are parts of said circuit, preferably inside the casing, associated with the bar 11. In neither is the bar 11 part of the circuit. In Figures 1 to 11 inclusive the 5 conducting means in the casing comprises parts 73, 23, 74, 75 and 76; and in Figures 10 to 14 inclusive, 73, 98, 76, 75, 100 and 102. Both forms include the means 45 for testing purposes, and the plunger or plungers 10 serving as means to return the spindle or spindles 76, and enable the ignition system to resume operation.

The spring 42^a is chiefly useful as means for desynchronizing; that is, if the bar 11 15 should oscillate in unison with the ordinary vibrations of the engine, the spring 42^a will prevent these oscillations from causing the bar to stop the engine under ordinary conditions when no accident has happened.

Screws 80 can be adjusted from the lower 20 side of the bar 11 to fix the point at which the elements 34^a and 74 will be engaged and made to release the dogs 75.

Having described my invention what I 25 believe to be new and desire to secure and protect by Letters Patent of the United States is:—

1. The combination of an element mounted to be movable in response to a shock, a 30 pair of springs engaging said element, means for adjusting said springs, and a third spring adjustably mounted adjacent said element to prevent operation thereof except under predetermined conditions.

2. Mechanism comprising a casing, a pair 35 of conductors leading into said casing, a pair of conductors leading out of said casing, elements for electrically connecting said conductors, a pair of spindles having dogs engaged by said elements, an element in the 40 casing mounted to move in response to a shock to actuate said first-named elements to release said dogs, indicating members carried by the casing and visible from the outside 45 of same, arms on said spindles to control the position to said members, a second arm on each spindle and a plunger for engaging said second arms to turn the spindles and restore said dogs to engagement with said pivoted elements.

3. The combination of a pair of contact elements, a dog to press the same into engagement, a catch for holding the dog out of operative position, and an element to be moved by a shock to release said catch.

4. The combination of a casing, a conductor in same, a spindle carrying a dog connected to said conductor, a contact element in circuit with said spindle, a second 55 conductor connected to said element, another

contact element adjacent said first named contact element, a pivoted element engaging said dog, a pivotally mounted bar to move the pivoted element to release the dog, whereby the dog will cause the contact elements to engage, an electrical conductor connected to said second contact element, an arm on said spindle and an indicating member controlled by said arm. 65

5. The combination of a casing having an 70 opening, a member bearing an indication, a spring engaging said member to move the indication into registry with said opening, a spindle having an arm engaging said member to keep said indication out of register 75 with said opening, a dog on the spindle, an element to engage the dog, and a spring to move the spindle to release said member when the dog is disengaged from said element. 80

6. The combination of a casing having an opening, a member bearing an indication, a spring to engage said member to move the indication into registry with the opening, a spindle having an arm engaging said member to keep same out of indicating position, a dog on the spindle, an element to engage the dog, a spring to move the spindle to release said member when the dog is disengaged from said element, another arm on the 90 spindle and a plunger to engage said arm and return the spindle, the dog, and the member. 85

7. The combination of a pair of contact elements, a spindle, a dog thereon, an element to engage and release the dog, and a spring to cause the spindle to rotate the dog when released to make said contacts disengage each other. 95

8. The combination of a pair of contact 100 elements, a spindle, a dog thereon, an element to engage and release the dog, a spring to cause the spindle to rotate the dog when released to make the contacts disengage each other, an arm on the spindle and a plunger 105 to engage the arm and make the element and dog reengage each other.

9. The combination of a pair of spring contact elements, a releasable dog to move said elements into engagement, a member, 110 and an arm movable with said dog to permit said member to assume an indicating position when said elements are in engagement, a second arm movable with the dog, and a plunger to engage said second arm to 115 return the dog and said member.

In testimony whereof, I have signed my name to this specification this 17th day of January, 1919.

THEODORE DOUGLAS.
